UNITED STATES PATENT OFFICE.

ALFRED SMALLWOOD, OF LONDON, ENGLAND.

FURNACE.

1,335,203.

Specification of Letters Patent. Patented Mar. 30, 1920.

Application filed July 31, 1918. Serial No. 247,643.

To all whom it may concern:

Be it known that I, ALFRED SMALLWOOD, a subject of the King of Great Britain, residing at 42 Hargrave Park, Highgate, London, N., in the county of Middlesex, England, metallurgist, have invented Improvements in or Relating to Furnaces, of which the following is a specification.

This invention comprises certain improvements in or relating to furnaces, and is particularly applicable to furnaces for heating the extremities of articles such as shells, bars, or the like.

According to the present invention, perforations are provided in the outer wall of a heating chamber through which the shells, bars, or the like are adapted to be projected. This heating chamber may be divided by partitions into a series of compartments or in other words there may be a series of chambers; in each chamber or compartment one or more perforations may be provided each for the reception of a shell, bar, or the like or an elongated opening may be provided for the reception of a series of shells, bars, or the like arranged side by side. From the side of the heating chamber opposite to that through which the shells, bars, or the like are projected, air and gas are adapted to be introduced. Flame produced by the combustion of this air and gas is directed downwardly upon the articles under treatment and the products of combustion pass through an opening or openings below the article or articles under treatment. This opening or these openings are regulable, as for instance by two regulators adapted to be closed toward each other, one on each side of the article under treatment. The products pass into a longitudinal flue or chamber below the heating chambers or compartments.

In order that this invention may be clearly understood and readily carried into practice, reference may be had to the appended explanatory sheets of drawings, upon which—

Figure 1 is a vertical side elevation of a furnace constructed according to the present invention, the plane of section being on line 1—2 of Fig. 2.

Fig. 2 is a vertical end elevation of the furnace shown in Fig. 1, the plane of section being on line 3—4 of the figure last mentioned.

Fig. 3 is a sectional plan, the section being taken on line 5—6 of Fig. 2.

Fig. 4 is a sectional plan, the section being taken on line 7—8 of Fig. 2, and

Fig. 5 is a sectional elevation being taken on line 9—10 of Fig. 1.

In a convenient embodiment of the present invention, as shown in the drawings, *a*, in Fig. 2 represents one of a series of heating chambers or compartments extending the length of the furnace and subdivided by partitions *b* shown in broken lines in Fig. 1. *c* is an opening into each chamber *a* through which the article such as *d* to be heated may be projected. Each opening *c* may be formed in a renewable fire-brick block *e'*. The opening *c* may be cylindrical at its inner part and coned at its outer part. *e* is a horizontal combustible gas or heat flue extending substantially the length of the furnace and adapted to receive combustible gas or heating gases from a gas producer or fire-grate *f*. From this longitudinal flue *e* a series of conduits *g* extend upwardly to a point at which they enter the upper parts of the chambers *a*. From Fig. 1 it will be noted that in the embodiment shown, two of the ports or conduits *g* are provided for each chamber *a*. Above the gas flue *e* and to the side of the conduits *g* remote from the chambers *a*, a longitudinal hot air flue *h* is provided adapted to supply hot air to the top parts of the chambers *a*. *i* represent communicating ports, two for each chamber *a*, by which air from the flue *h* passes into said chambers *a*. The ports or conduits *g* and *i* are all individually regulable. This individual regulation may be effected by dampers adapted to be operated through openings *j*.

k represents a longitudinal waste gas flue located below the chambers *a*. *l* represents one of a series of egress ports offering communication between each chamber *a* and the waste gas flue *k*. The port *l* may be regulable, as for instance by a bung or damper *m*. Air and gas admitted by the ports *g*, *i* burn with a flame which descends upon the inwardly projected extremity of the article *d* under treatment, and the flame or products egress by way of the opening *l* to the waste gas flue *k*. *n* represents a slag hole located below the opening *l* by which slag may be removed as desired.

At the rear extremity of the furnace the waste gas flue *k* communicates by a depending flue *o* and transverse flue *p* with four waste gas flues *q*, which extend forwardly.

These waste gas flues *q* communicate at their front extremities with four other waste gas flues *r* located below the flues *q*, and which waste gas flues *r* communicate at their rear extremities with a transverse flue *s* leading to the stack. *t* is a transverse air flue to which air is admitted by any suitable provision. The transverse air flue *t* communicates with a series of rearwardly extending air flues *u* 5 which at the rear of the furnace communicate with an upper series of forward air flues *v*. The upper air flues *v* communicate at their front extremity with a transverse air space *w*, which communicates with a series of rearwardly extending air flues *x*. These rearwardly extending air flues *x* communicate at their rear extremities with an 10 ascending hot air flue *z*, which adjoins the hot air flue *h*. An efficient recuperator system is thereby provided whereby the air in the flue *h* is heated by the waste gases from the flue *k*. As shown, the recuperator system may extend only a part of the length of the structure in order to leave room for the 15 gas generator or fire-grate *f*.

The system may be so regulated that a slight pressure exists in the heating chambers or compartments so that no air enters in the spaces around the articles under treatment. This pressure can be so balanced that only a slight amount of heat, if any, escapes through the openings around the articles 20 under treatment.

What I claim as my invention and desire 25 to secure by Letters Patent is:—

1. A furnace, including a heating chamber having an aperture in the wall thereof for the introduction of articles to project into said heating chamber, the heating 30 chamber being divided into a plurality of compartments, a heat distribution chamber communicating with said heating chamber, and a hot air chamber in the form of a flue running longitudinally of the plurality of heating compartments.

2. A furnace, including a heating chamber having an aperture in the wall thereof for the introduction of an article to project into said heating chamber, said heating 40 chamber being subdivided into a plurality of compartments, a hot air chamber located on the side of the heating chamber opposite to that through which the articles are introduced, and a heat distribution chamber arranged below said hot air chamber and having the form of an elongated chamber located longitudinally of the plurality of heating compartments.

3. A furnace, including a heating chamber having apertures in the wall thereof for the introduction of articles to project into said heating chambers, said heating chamber being subdivided into a plurality of heating compartments, a hot air chamber arranged 45 on the side of the heating chamber

opposite to that through which the articles are introduced and communicating with said heating chamber, a heat distribution chamber arranged below said hot air chamber, and conduits extending from said heat distribution chamber to said heating compartments, said conduits being located intermediate of said heating compartments and the hot air chamber. 70

4. A furnace, including a heating chamber 75 having an aperture in the wall thereof for the introduction of an article to project into said heating chamber, a hot air flue located on the side of the heating chamber opposite to that through which the articles are introduced and communicating with said heating chamber, a heat distribution chamber located below said hot air chamber and communicating with said heating chamber, and a waste gas flue underneath said heating 80 chamber and running longitudinally thereof.

5. A furnace, including a heating chamber having an aperture in the wall thereof for the introduction of an article to project into said heating chamber, a hot air chamber arranged on the side of said heating chamber 85 opposite to that through which the articles are introduced and communicating with said heating chamber, a heat distribution chamber arranged subjacent to said hot air chamber 90 and communicating with said heating chamber, a waste gas flue located below the heating chamber and extending longitudinally thereof, and a recuperator system disposed below said waste gas flue and said heat distribution chamber and adapted to heat the air supply to said hot air chamber by means of the waste gases egressing from said waste 95 gas flue. 100

6. A furnace, including a heating chamber 105 having an aperture in the wall thereof for the introduction of an article to project into said heating chamber, a hot air chamber arranged on the side of said heating chamber opposite to that through which the articles are introduced and communicating with said heating chamber, a heat distribution chamber arranged subjacent to said hot air chamber and communicating with said heating chamber, a waste gas flue located below the heating chamber and extending longitudinally thereof, a recuperator system disposed below said waste gas flue and said heat distribution chamber, and adapted to heat the air supply to said hot air chamber 110 by means of the waste gases egressing from said waste gas flue, and a gas producer arranged below the waste gas flue and heat distribution chamber. 115

In witness whereof I have hereunto set my hand in the presence of two witnesses.

ALFRED SMALLWOOD.
